UNITED STATES PATENT OFFICE.

CHARLES S. WILLIAMSON, OF CHICAGO, ILLINOIS.

COAL-HANDLING PLANT.

1,315,439.

Specification of Letters Patent. Patented Sept. 9, 1919.

Original application filed February 26, 1916, Serial No. 80,577. Divided and this application filed March 22, 1917. Serial No. 156,611.

To all whom it may concern:

Be it known that I, CHARLES S. WILLIAMSON, a citizen of the United States, residing at Chicago, in the county of Cook and State 5 of Illinois, have invented certain new and useful Improvements in Coal-Handling Plants, of which the following is the specification.

It is an object of the invention to provide 10 mechanism of a novel kind for taking coal from a hopper into the cars of a cable or equivalent system, this mechanism eliminating to a large extent, the heretofore unavoidable dropping and consequent break- 15 age of the coal.

In the drawings:—

Figure 1 is an elevation of the entire system constructed according to my invention.

20 Fig. 2 is an enlarged cross sectional view of the mechanism for loading cable cars.

Fig. 3 is an elevation of the car loading mechanism.

25 Fig. 4 is a transverse cross sectional view thereof.

Fig. 5 is a detailed plan view illustrating the control for the plunger comprising a part of mechanism for loading the cable cars.

30 Fig. 6 is an enlarged elevation, partly in cross section showing the control means for the plunger operating mechanism.

This application is a division of my co-pending application, Serial Number 80,577, 35 filed February 26, 1916.

Reference being had to the drawings, 1 represents a storage yard or the like, in connection with which is a car dumper 2, to which railroad cars are sent from the 40 storage yard 1, and from which tracks 5 lead out, upon which are operated cars 4, which it is an object of this invention to load in a novel and efficient manner. Underneath the car dumper 2 are located preferably a plurality, in this instance 4 bins, 6. The mechanism for loading the cars 4 from the hopper 6 supplied by the car dumper embodies many important advantages.

Reference being had to Figs. 2, 3 and 4, 50 Fig. 3 represents one of the hoppers associated with the car dumper, four such hoppers being in this instance provided, arranged successively along and over the cable car track and supported on suitable structural steel supports. The hopper 6 is pro-

vided with a front wall 11 suitably supported by I and channel irons 12 and provided near its bottom with a reverse angle 13, while the rear wall 14 of the hopper 6 is continuous past the angle 13 so as to provide an inclined and constricted passage 15 leading to the bottom 17 of the hopper. The front wall 111 of the hopper below the angle 13 is cut off so as to leave a considerable space between its lower edge and the bottom of the hopper. The coal is shown in the hopper in Fig. 2, its angle of repose being indicated by the line R. Firmly mounted upon the channel beams 12 forming the structural support for the hopper are channel irons 18 which support the floor 17 and to which are fastened side plates 19 extended forward with the floor 17 to confine the coal at the sides of the hopper and also provided with a rearwardly extending portion 19' 70 to carry the plunger to be described. Inner linings 20 are provided in hopper 6 and are constricted as indicated at 21 so as to leave a space between them and the outer side walls 19, braces 22 reinforcing the 75 angles. In these spaces thus formed are firmly secured angle iron tracks or runways 23 extending the entire length of the side plates 19 including the extensions 19'. Running upon the tracks 23 are wheels 24 80 of carriages or standards 25 bolted to racks 26, which are firmly fastened (as by welding) to the top plate 27 which with the face of plate 28 forms a plunger for loading the cable cars. The top plate 27 and the face 85 plate 28 are held in correct position by suitable reinforcements 29 as indicated in Fig. 2 and suitably secured to these reinforcements 29 are braces 30 bolted to the racks 26 which as stated are in turn welded or 90 otherwise suitably secured to the top plate 27. The plunger structure is thus strongly reinforced and braced throughout.

The face plate 28 is adapted to snugly fit in and completely occupy the recess between the bottom of the rear wall 14 of the hopper and its floor 17, and between the side plates 19 below the constricted portion 21 of the hopper.

Mounted upon a shaft 35 in the side plates 105 19 is a gate comprising curved web 36 integrally connected at both ends to sectors 37 mounted at their angles upon the shaft 35. The gate 36 is operated in conjunction with the plunger 28 and is moved downwardly 110

at the proper time into dotted line position (see Fig. 3) so as to permit coal to be pushed over the edge of the floor 17 into cars traveling below by the plunger at each 5 of its operations. It is operated by a link 40 connected to a crank 41 upon a suitable shaft provided with a gear 42 operated by a rack 43, in turn operated by air cylinder 44, the control for this cylinder being similar to or a part of that for the plunger 28 hereinafter described.

Pivottally mounted in the side plates 19 are a pair of sector arms 45 and integrally connecting their bottoms is a curved web similar 15 to that forming gate 36 and adapted to form a closure for an opening 47 in the floor 17 of the hopper just behind the retracted position of plunger 28, the opening 47 being bounded by angle irons 49 slightly larger than angle irons 20 50 forming part of the structural support for the hopper. The construction just described is provided to catch coal dust caused to move backwardly on each return stroke of the plunger and discharge this dust into a car 25 beneath the hopper saving approximately a handful of dust on each stroke and aggregating an appreciable amount of coal in the day's operation. The members 45 are operated in an obvious manner by a bent link 30 51 connected to one of sector members 37 running on roller 52 in the side plates 19 and adapted to impinge the pin 53 mounted in the sector member 45, so that each time the gate 36 is moved into position shown in the 35 dotted line in Fig. 3 the bucket structure 45 will be quickly thrown to one side dumping the accumulated dust into the car below.

I will now describe the mechanism for operating the plunger 28, it being of course 40 understood that any other means than the specific one here described and capable of doing like work could be substituted therefor without departing from the broad features of the invention. Reference being had 45 to Figs. 5 and 6, it will be seen that I provide a series of electrical contacts 55, 56, 57, 58, 59 and 60, there being as many of these contacts as necessary to fit the requirements of any particular situation. These contacts 50 are adapted to be closed by shoes on the cable car and operate valves 61, 62, 63, and 64, as many of these valves as required to fit the particular situation being employed. The contact 55 acting through solenoid 55' 55 operates to start the associated plunger forward by letting air into the pneumatic apparatus to be described. The contact 56 when closed, causes the valve to be closed again through solenoid 56' stopping the 60 plunger. The contact 57 acting through solenoid 57' and valve 62 returns the plunger. The contact 58 acting through solenoid 58' again closes the valve. The contacts 59 and 60 acting through their associated 65 solenoids again operate the plunger. It will

be readily seen that the pneumatic mechanism controlled by the valves 61, 62, 63, etc., comprises a cylinder in which is mounted a piston 71 rigidly connected with the rod 72, the cylinder 70 being provided with a head 73 screwed therein and also screwed to the sleeve 74 in which the rod 72 slides, which sleeve 74 is mounted in a thrust bearing 75. Air is supplied to cylinder 70 through tube 76 in communication with one of the valves 75 61, 62, etc. The rod 72 is connected adjacent thrust bearing 75 with collar 77 having an extended hub 78, bearing against the hub 79 of a gear 80 provided with a conical friction face 81, the collars 75 and 79 being 80 mounted upon the journal 82 forming a continuation of sleeve 74 as does the sleeve 83 mounted in the thrust bearing 84, a slotted connection being provided to permit the collar 77 to move longitudinally with the rod 85 72. The entire construction described is duplicated in the left hand side of Fig. 6 though the parts do not appear as they do in the right hand or sectional side of the drawing.

Rotatably mounted upon the sleeves 83 are bevel gear pinions 85 having friction faces adapted to coöperate with friction faces 81 as clearly seen, and equipped with springs (not shown) 86 to separate the friction surfaces. From the construction so far described, it will be apparent that admission of air to one of the tubes 76 will push the rod 72 and therefore the rear friction face 81 into frictional engagement with the 95 nearest bevel pinion 85 and release the engagement of the other bevel pinion so as to rotate the gear 87 in one direction or the other. The gear 87 is rigidly mounted upon the shaft 88 which is provided with bearings 100 in the side plates 19 of the hopper and carries the gears 89 in mesh with racks 26 connected to plate 27 of the plunger as above explained.

The drive for gears 80 is provided by the shaft 90 having thereon gears 91 in engagement with each of the gears 80 and continuously driven by means of an electric motor 91 or by equivalent means driving through pinion 92 and a large gear 93. By the mechanism just described it will be apparent that as each car proceeds under one of the hoppers the associated plunger will move forwardly to deposit a load therein and then move backwardly into retracted position 110 ready for the next load.

It will be clearly seen that with the plunger in its retracted position (see Fig. 2) the coal will rest upon the floor 17 of the hopper in front of the plunger, the line of repose of the coal being shown by the line R. When the plunger moves forwardly the mass of coal between the line R and dotted line P, Fig. 2, will be gently shoved forward over 125 the front edge of the floor 17 and deposited 130

in the car immediately below. The coal above the line P simply slides down into and rests upon the plate top 27 of the hopper as the same moves forward. As the plunger 28 is retracted after having deposited the mass of coal M in the car below, the coal will drop down over its front plate 28 onto the floor 17. The gate 36 is provided to prevent coal "splashing" out of the hopper at this time.

I considered the plunger loading apparatus just described in detail of great importance for the reason that it is the first so far as I am aware, to provide for loading cars without leaving a very considerable clearance between the loading apparatus and the car made necessary by turning, upsetting or other similar movement of the actual loading device in loading the car. By employing a plunger movable in the same plane as the car, I may make the clearance between the car and the loading apparatus just as small as practicable to permit a car to pass under the bottom of the hopper, and the device will operate perfectly to deposit coal from the car into the hopper. This reduces the "drop" of the coal by many inches and very largely diminishes breakage. Furthermore, and as an important feature of this invention, the coal is moved forwardly by the plunger in the same direction as that in which the car is going, so that practically all the shock or jar of the coal in a horizontal direction as it is dumped into the car, is eliminated, the coal and the car moving together at practically the same speed when they come together. With the horizontal jar upon the coal eliminated and more important the great reduction in its "drop", I very greatly reduce the breakage.

In the particular modification of the invention herein disclosed, I provide four hoppers each provided with a plunger as just described and each adapted to push a quarter of the full car load into the car passing underneath it so that a four ton car (for instance) going under the four hoppers picks up a ton from each hopper. This method of instalment-loading reduces breakage and makes the operation simple and faster than to load the full load in one charge.

Having now described my invention, I claim:—

1. In apparatus of the class described, a hopper, a trackway associated therewith, a plunger moving in a plane parallel with the trackway, and means for operating said plunger to push a load of coal from said hopper out of the same into a subjacent car, said means automatically operating upon the successive passage of the cars.

2. In apparatus of the class described, a hopper having a constricted portion, a bottom extending beyond said constricted por-

tion, automatically operated plunger mechanism moving over said bottom and adapted to push a load of coal or the like over the edge of said bottom upon the passage thereunder of cars, means for preventing said coal or the like from spilling over the edge of said bottom when said plunger is in a retracted position, and means for rendering said preventing means inoperative when said plunger is operating to discharge said coal or the like.

3. In apparatus of the class described, a hopper, adapted to contain coal or the like, a passageway extending through said hopper adjacent its bottom, a plunger device adapted to reciprocate in said passageway to push the material filling the same out of the hopper, means to catch the dust snapp'd up by said plunger on its return stroke.

4. In apparatus of the class described, a hopper adapted to contain coal or the like, a passageway extending through said hopper adjacent its bottom, a plunger device adapted to reciprocate in said passageway, a gate adapted to prevent coal or the like from accidentally falling out of said hopper, and means to raise said gate upon the operative motion of the plunger device.

5. In apparatus of the class described a hopper having a constricted portion, a chamber below said constricted portion, a plunger adapted to reciprocate in said chamber to push a load of coal or the like therefrom, an opening in the side of the chamber, and a gate operable to open as said plunger advances.

6. In apparatus of the class described a hopper, a receiving compartment below said hopper, an opening in the front of said compartment, a plunger adapted to reciprocate in said compartment to push a load of coal or the like through said opening, a gate operatively mounted over said opening, a second opening in the bottom of said compartment and behind said plunger, a gate over said second opening, and means to operate both of said gates in unison as said plunger advances.

7. In apparatus of the class described a hopper having an inclined rear face and terminating in a passageway closed at the bottom and two sides, a plunger fitting in said passageway and comprising a front face and a top plate, means for reciprocating said plunger to discharge coal or the like from the hopper, an opening in said bottom and behind said face, and a gate over said opening and operable to open to permit the ejection of coal dust into a car beneath.

8. In apparatus of the class described a plurality of hoppers, each having a constricted portion with an open ended chamber therebeneath, a plunger in each of said chambers, means to automatically and successively operate said plungers to discharge

coal or the like from said chambers into a car beneath, said plungers each discharging such a fractional portion of a carload from its respective hopper that when said car has 5 passed all of said hoppers it will have its full load.

9. In apparatus of the class described a hopper having a constricted portion, a trackway below said hopper, a car movable 10 along said trackway, a reciprocating plunger below said constricted portion and adapted to discharge coal or the like therefrom into said car, a rack on said plunger,

a pinion engaging said rack, and reversible gearing connected for driving said pinion 15 to operate said plunger, said gearing being automatically controlled by the passage of said car beneath said hopper.

In witness whereof, I hereunto subscribe my name to this specification in the presence 20 of two witnesses.

CHARLES S. WILLIAMSON.
